UNITED STATES PATENT OFFICE.

HENRY L. PITMAN, OF EAST ORANGE, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,332,233.

Specification of Letters Patent.

Patented Mar. 2, 1920.

Application filed January 27, 1917. Serial No. 144,825.

To all whom it may concern:

Be it known that I, HENRY L. PITMAN, a citizen of the United States, residing in East Orange, in the county of Essex and State of New Jersey, have invented certain new and useful Improvements in Combined Typewriting and Computing Machines, of which the following is a specification.

This invention relates to a combined typewriting and computing machine and more especially to the type known as key-driven machines, and is an improvement on my application, Serial No. 24,390, filed April 28, 1915. The present improvement deals more specifically with ultra-decimal computations in connection with decimal computations.

In certain types of work it is desirable to have on the work-sheet decimal items and other items which may not be entirely decimal. The present machine is arranged to take care of such classes of work whereby the same master wheel mechanism may drive computing heads or totalizers which are wholly decimal, other computing heads or totalizers which are partly decimal and partly ultra-decimal and even computing heads which are arranged to compute in the sterling system. This is accomplished by varying the driving ratio within the computing head itself, so that the master wheel mechanism which is driven by the numeral keys may be substantially the same. The mechanism for carrying over from the fraction dial wheels to the decimal dial wheels is arranged to avoid interference with the additional gearing to the fraction dial wheels, and to carry properly to the decimal dial wheels.

Other features and advantages will hereinafter appear.

In the accompanying drawings,

Figure 1 is a vertical section from front to rear of the machine with parts omitted to simplify the showing.

Fig. 2 is an enlarged front view in elevation showing the driving of one of the totalizers which computes decimal and in twelfths.

Fig. 3 is a view showing the arrangement of the numeral keys for computing twelfths with the associated type heads which are arranged to print the whole numbers in lower-case and in fractions in upper-case.

Fig. 4 is a fragmentary view in elevation,

looking from the back forward, with parts in section to show the arrangement of drive and carrying for a fractional dial wheel.

Fig. 5 is a spread perspective view showing the driving arrangements and carrying train for a fractional dial wheel computing twelfths.

Fig. 6 is an enlarged vertical section taken from front to rear through one of the totalizers at a point showing a decimal dial wheel and mechanism for driving same.

Fig. 7 is an enlarged view similar to Fig. 6, showing the driving and carrying mechanism for a fractional dial wheel computing twelfths.

Figs. 8, 9 and 10 are views similar to Fig. 7, showing dial wheels arranged to compute eightths, fourteenths and twenty-fourths, respectively.

Fig. 11 is a fragmentary view in front elevation showing three different types of computing heads which may be used with a single actuator or master wheel mechanism.

Fig. 12 is a view similar to Fig. 3, except that it shows an arrangement of keys and type-heads for computing eightths as well as whole numbers.

Fig. 13 is a detail perspective view of a dial wheel, like the one of Fig. 5, for computing twelfths, and adapted to compute pence.

Alphabet keys 1 and numeral keys 2 depress key levers 3 to rock bell cranks 4, so as to swing type-bars 5 up rearwardly against the front side of a platen 6, mounted to rotate on a carriage 7. The carriage 7 travels on ways 8 under the impulse of a spring barrel (not shown). The movement of the carriage is step by step under the control of the keys. This is done by providing a rack 9 pivotally connected to the carriage and meshing with a pinion 10 controlled in its rotation by an escapement wheel 11, alternately engaged by fixed and pivoted dogs 12. The dogs 12 are rocked by a universal frame 13, which in turn is rocked by heels 14 provided on each of the type-bars 5.

Each of the type-bars 5 is provided with two different types 15 and 16, the former being lower-case and the latter upper-case types. For the numeral keys, the lower-case types 15, which are ordinarily in use, are whole numbers, while the upper-case types 16 are fractions.

The invention is intended to include computing in different systems of measurement such as the English or sterling monetary system, which computes in twelfths, tenths or decimal, and other fractional measuring systems such as twenty-fourths, fourteenths and the like. The amounts printed by the numeral keys 2 through the associated types 15 and 16 are so adjusted that they always 5 bear the same proportion to each other, whatever their actual magnitude. For example, for the computing head mechanism shown in Figs. 2, 4 and 5 having a fraction wheel, which will compute in twelfths, the 10 numeral keys in addition to the whole numbers 1, 2, 3 up to 9 are inscribed with fractional indications $\frac{1}{2}$, $\frac{1}{3}$, $\frac{1}{4}$, etc., up to $\frac{1}{12}$, respectively. Two additional keys are provided for 10 and 11 and their fractions $\frac{1}{12}$ 15 and $\frac{1}{12}$. This is shown in Fig. 3, which also discloses that the corresponding types have the same whole numbers and fractional values to correspond with their associated keys. As indicated in Fig. 12, a set of types is 20 adapted to be used for computing eighths, and the keys are correspondingly marked with the whole numbers and fractions which they are to compute and typewrite.

In order to enable the change from printing in whole numbers, or lower-case characters, to printing in upper-case, or fractional characters, when computing fractional values, there are provided one or more case-shift keys 17, which, when one of them is 25 depressed, rocks a key lever 18 to swing forward an arm 19 engaging in back of a shift frame 20 mounted to oscillate about the axis of a shaft 21. The shift frame 20 is provided at its forward end with a shift 30 rail 22 engaging under a plurality of rollers 23, so as to raise an inner carriage or frame 24 on which they are mounted. This inner carriage or frame supports the platen 6 and, in turn, is mounted on the carriage 7 by 35 means of arms 25 whereby it may have its up-and-down movement.

In the present improvement the numeral keys are arranged to compute, when typewriting, with both upper and lower case 40 types. For this purpose each of the numeral keys is provided with a differentiator 26. These differentiators have cam slots 27 therein, which are varied in their conformation according to the values of the associated 45 keys so that they will give graded rocking movements to a bail 28 according to the values of the operated numeral keys. That is to say, the "1" numeral key will give one unit of movement, the "2" numeral key two 50 units of movement, the "3" numeral key three units of movement, and so on up to the maximum.

The bail 28 is provided with a pin 30, which, when the machine is connected for 55 computing, as well as typewriting, engages

between pommels 31 on a humpback interponent 32 and forms part of an oscillator which includes a lever 33 pivotally mounted on a shaft 34. The interponent 32 is pivoted to the lever 33 at 35 and is normally held by means of a spring 36 with the dip therein between the pommels 31 located in engagement with the pin 31, so as to form a positive connection between the oscillator and the bail. That is to say, the position of the interponent 32 determines whether the machine will be operated for computing purposes as well as for typewriting, or solely for typewriting. Ordinarily, with the spring 36 in action the mechanism will be 70 capable of computing as well as typewriting. If it should be desired to silence the computing part of the mechanism the interponent 32 will be depressed out of operative connection with the pin 30, and thus the bail 28, 75 by means of a shifter 37, engaging the same. This shifter is rocked by a link 38, in turn actuated by a handle 39.

If the handle 39a is in its connected position every time a numeral key is actuated, 80 the oscillator including the lever 33 will be rocked an amount corresponding to the particular numeral key actuated. This in turn will draw down on a link 39, so as to rock a bell crank 40 located adjacent to the upper 85 front of the typewriting machine frame 41. The other arm of the bell crank 40, than that with which the link 39 is connected, swings forward a link 42, which is connected at its front end to a rack 43. The rack 43 is normally in mesh with a pinion 44, so that during this forward movement the pinion 44 will be rotated an amount corresponding to the particular numeral key actuated. This 90 valuating or indexing driving movement of the pinion 44 and the shaft 45 on which it is mounted takes place during the first part of the down stroke of the actuation of a numerical key.

In order that the numeral key and the 100 rack 43 actuated by the numeral key may return idly, it is disconnected from the pinion 44 so as to be ineffective thereon at the very last part of the down stroke of the numeral key. This is done by the universal 110 frame 13 which is actuated to effect an escapement movement of the carriage. That is to say, the same action which starts an escapement movement of the carriage also disconnects the rack bar 43 from the pinion 44. 115

The universal frame 13 when oscillated backward swings rearwardly the upper part of a supporting frame 46 on which it is pivotally mounted. On the opposite side of a pivot 47 of this swinging frame is provided 120 an arm 48 which swings upwardly an engaging arm 49. The arm 49 is secured to a shaft 50 which it rocks, and the latter is provided with a second arm 51 which is rocked thereby. The arm 51 thrusts for 125

ward a link 52, which in turn rocks a double bell crank 53. One arm of the bell crank is connected to the link 52, a second arm 54, Fig. 6, is provided with a pin 55, engaging 5 in a slot 56, in the driving rack bar 43. A third arm 57, of this bell crank, is connected by a link 58 to one arm 59 to another bell crank 60, pivoted at 61. This causes the bell cranks 53 and 60 to move in 10 unison and have a substantial parallel motion. A second arm of the bell crank 60 is provided with a pin 62 which engages a second slot 63 in the driving rack bar 43.

It will thus be seen that no matter what 15 the forward extent of driving movement the rack bar 43 has had when the actuated numeral key makes its downward movement and thus completes the extent of its valuating or indexing drive, the act of the type-bar in operating the escapement universal frame 13 will cause, through the connected mechanism, a horizontal downward movement of the driving rack bar 43 so as to disconnect it from the pinion 44. The same 20 movement that disconnects the driving rack bar also insures that the pinion 44 shall not be overthrown or accidentally moved when the rack bar 43 is disconnected therefrom. For this purpose the double bell crank 60 25 is provided with a third arm 64 which has a locking tooth 65 forced into engagement between the teeth of the pinion 44 as the bell crank 60 rocks to disconnect the rack bar 43. When the numeral key returns, the 30 driving rack bar is also returned, but idly, with respect to and disconnected from the pinion 44. In order that the driving rack bar 43 may not have a subsequent forward movement before it has completed its re- 35 turn movement, the lower side of the rack 43 has one-way facing teeth 65^a engaged by a spring pawl 66. A premature reengagement of the driving rack 43 is prevented by a lock 160 whose function and action are 40 more particularly described in my application 45 above mentioned. Sufficient is to say that this lock maintains the rack bar in its depressed position until it arrives at its home position, when the lower arm of the bell-crank 40 trips the latch by engagement 50 with a stop 161, so that as the numeral key reaches its normal raised position, the rack will be permitted to reengage the gear 44 and the carriage-escapement mechanism permitted to act.

The pinion 44 is of the barrel type, see 55 Fig. 2, so that it can be shifted along the shaft 45 and still maintain its driving relation with the rack bar 43. The shifting is 60 done so that a gear 67 secured for rotation therewith may selectively mesh with a gear 68 or a gear 69. The gear 69 drives the gear 68 through the intermediary of a gear 70 secured to a common hub 71 with the gear 69. That is to say, the gear 67 may drive the

gear 68 either directly, for a rotation in one direction, or indirectly through the gears 69 and 70, effecting a rotation in the opposite direction. In one case it will cause an adding computation, and in the other case a 70 subtracting computation. The gear 68 is connected to drive a master wheel 72. The master wheel may drive individual computing wheels 73 of one or more totalizers or computing heads 74. The dial wheels 75 are in the form of gears having thick broad teeth, so that the digits and fractions which they compute may be inscribed on the points of the teeth, as shown in Fig. 13. The connections between the computing wheels 73 and the dial wheels 75 which they drive will be more or less direct according to whether the dial wheels compute decimal or in common fractions.

There are a number of different styles of 85 heads embodied in the present invention. In fact, the present invention is intended to include the use of two or more different styles of computing heads for one travel of the carriage. For example, as shown in Fig. 90 11, three different types of heads are used on the machine at the same time. Head "A" is a straight decimal computing unit. Head "B" is a decimal computing unit with the addition of a wheel for computing twelfths. Head "C" is a sterling computing unit arranged to compute pounds, shillings and pence. As shilling is merely a decimal order, the only wheel which is an ultra-decimal wheel will be the pence wheel, which 95 computes twelfths. Other styles of computing heads having the wheel of lowest denomination computing in other common fractions, may be used. In Figs. 7, 8, 9 and 10, fractional wheels computing, respectively, twelfths, eighths, fourteenths and twenty-fourths, are shown. For the computing wheels of higher denomination than the lowest, inasmuch as they are all decimal, a direct drive, such as that shown in 110 Fig. 6, may be used, where the gear 73 actually meshes with and drives the dial wheel 75. In the case of the fractional dial wheels which are wheels of lowest denomination, indirect drives from the gears 73 are used. 115 The distance between the axes of the gears 73 and 75 are maintained the same in all cases, so that all the computing wheels and all the dial wheels are respectively of one size, and each set of wheels is journaled on 120 a single axle. The variations of the driving ratio are obtained by intermediate gears meshing with the gears 73 and 75, and the use of these intermediate gears is made possible by having the markings on the fractions wheel in such order that it can turn oppositely to the decimal wheels in effecting computations.

In the case of twelfths, as shown in Figs. 5 and 7, a thick toothed gear 77 is driven 130

4

by the gear 73; the teeth being six in number, viz., the teeth of a twelve-toothed wheel with spaces between the alternate teeth filled in and having the same pitch as 5 the gear 73. Fixed to the gear 77 there is provided a gear 78 having six teeth like the gear 77, except that the alternate teeth are cut away, so that the remaining teeth mesh with and drive the dial wheel 75 having 10 twelve teeth for computing twelfths. As stated above, each tooth of the dial 75 is made thick and broad so as to have the numbers, or, in this case, fractions which they compute, inscribed on the points of the teeth. 15 The gear 77 is rotated twice in one and two-tenths of a revolution of the gear 73, and the pinion 78, in turn, will rotate the dial wheel or gear 75 one complete revolution, or twelve units of movement. 20 For a fractional dial wheel computing eighths, viz., a base smaller than 10, as shown in Fig. 8, two intermediate gears are also used similar to those in Fig. 7. The first gear meshing with the gear 73, indicated at 79, has but four thick teeth, so that it will complete two revolutions when the gear 73 has made but eight-tenths of a revolution. The gear 79 has another gear 80 of 25 substantially the same diameter with twelve teeth therein, which meshes with a twenty-four tooth gear 81; secured to the eight-toothed dial wheel or gear 75. The dial wheel or gear 75 has in this case the eight fractional parts of a unit inscribed in order 30 on the points of the teeth which are thick and broad for this purpose, the same as the other dial wheels. In Fig. 9, a fraction dial wheel 75 computes fourteenths and is driven from the usual gear 73 by a seven-tooth gear 82 meshing with gear 73 having 35 fixed to it a seven-tooth gear 83, which meshes with and drives the dial wheel 75. In the case of computing twenty-fourths, as shown in Fig. 10, a twelve-tooth gear 84 of 40 proper diameter is driven by the gear 73 and has secured thereto a twelve-tooth gear 85. Gear 85 meshes with and drives the dial wheel 75 which has twenty-four teeth in this case. 45 For the purpose of carrying tens in the case of the dial wheels which are decimal, every tenth tooth on the gear 73 is broadened, as at 86, Fig. 2, so as to drive the opposite one of a series of tens-carrying gears 50 87 mounted to rotate co-axially with the master wheel 72. As the computing heads are mounted on the typewriter carriage 7 to travel with the same, the tens-carrying wheels 87, like the master wheel 72, are 55 stationary. At each letter-space stopping point of the carriage, and thus of the computing heads, the tens-carrying wheels 87 will overlap two of the gears 73, the lower gear to the extent of engaging the broad 60 tens-carrying teeth 86, and the upper gear 65

to the extent of engaging all of the teeth, so as to drive the same. It will be seen that at each punctuation space gears 73 are of double width.

As described in my application above-mentioned, care is taken so that the gear 73 will not get out of register with the master wheel or the tens-carrying wheels. Provision is also made so that the tens-carrying wheels will be locked, except when 75 actually in use for a tens-carrying operation. The structure for accomplishing this comprises locking dogs 88 engaging carry-over wheels 87 and held in action lightly by means of springs 89, operating on bell 80 cranks 90 which in turn engage the dogs 88; it also comprises a bail 91 operated by a rather strong spring 92 engaging all of the dogs 88. Positive locking is accomplished by levers 93 carried by the totalizers and 85 normally held with the lower ends 94 thereof in back of the dogs 88 to block their unmeshing with the tens-carrying wheels 87. When the corresponding gear 73, and associated dial wheel 75 make a revolution, a depression 95 in the gear 73 permits an enlargement 96 on the lever 93 to drop therein so as to admit of a rocking of the lever 93 and thus a release of the corresponding dog 88. 95

In the case of the totalizers computing ultra-decimally, the carrying from the lowest computing wheel to the next higher computing wheel is more indirect. In Fig. 5, where a dial wheel computing twelfths is shown at 100 the upper side thereof, there is secured for rotation therewith a gear 97, which meshes with and drives a gear 98 having secured thereto a single tooth starting, or carry-over gear 99. This carry-over, or starting 105 gear 99, once in every revolution of the dial wheel 75 rotates a ten-tooth gear 100 one-tenth of a revolution. This gear 100 is secured to a shaft 101 on which is formed a shoulder 102, on which the gear 110 73, which drives the twelfth computing dial wheel, is rotatively mounted. The gear 73 is spaced from the gear 100 by means of a shoulder 103. Secured to the shaft 101 on the opposite side of the gear 73 from 115 the gear 100 is a ten-tooth gear 104, which may be considered a carry-over wheel and which corresponds in dimensions to the gear 73 and meshes, through the intermediary of a carry-over wheel 87, with the next 120 higher dial wheel. This meshing with the carry-over wheel 87 results from the fact that the gear wheel 73 of Fig. 5 occupies only the part of a letter-space occupied by the narrow teeth of the ordinary computing wheels, while the gear wheel 104 covers only the space of the extensions 86 of the computing wheel teeth. Thus it will be observed that although the twelfths dial 125 wheel is spaced somewhat from the adjoin- 130

ing wheel, the twelfths may be printed in the column adjoining the next digit. In the case of the totalizer "B", this will be the units dial wheel computing decimally, 5 while in the case of the totalizer "C", it will be the units of shillings dial wheel, also computing decimally. A similar train of gearing can be used in the case of totalizers computing in common fractions, other than 10 twelfths, so as to take care of the carrying from the computing wheel of lower denomination to the higher computing wheels of decimal character.

The totalizers 74 travel with the type-writer carriage 7 in the manner described 15 in my above-mentioned application, and are held thereon by a latch 105 which engages in a rack 106, mounted on the carriage. To prevent the computing wheels from rotating 20 when not being driven, there is provided a detent 107 held in action by a spring 108. This detent is released by the driving rack bar 43 as it starts forward in its movement. For this purpose the rack bar is 25 provided with a depression 109 in which an arm 110 rests when the driving rack bar 43 is in its home position. When the rack bar starts forward it cams the arm 110 on to a level 111, which action causes the arm 30 to rock a second arm 112 secured thereto. The arm 112 engages and rocks a bell crank 113 which has a hook 114 arranged to release the lock 107. The bell crank 113 is also provided with a wedge 115 arranged to 35 engage between teeth 116 of a rack provided on each of the totalizers, so as to justify the position of the gears 73 with respect to the master wheel and the carry-over wheels, and also so as to prevent any traveling movement 40 of the totalizer in action while the master wheel is actually driving the computing wheels.

Variations may be resorted to within the scope of the invention, and portions of the 45 improvements may be used without others.

Having thus described my invention, I claim:

1. The combination with a decimal dial wheel, of a non-decimal dial wheel of lower 50 denomination than said decimal dial wheel, a computing wheel in mesh with said decimal dial wheel, a shaft on which said computing wheel is mounted, a sleeve concentric with said shaft, a computing wheel for said 55 non-decimal dial wheel loosely mounted on said sleeve, gearing whereby said last-mentioned computing wheel actuates said non-decimal dial wheel, a train of gearing by means of which said non-decimal dial wheel, upon the completion of 60 each rotation, turns said sleeve one step, and means, including a gear wheel fixedly mounted on said sleeve between the computing wheel for the non-decimal dial wheel 65 and the computing wheel for the decimal

dial wheel, for transmitting said single step movement of said sleeve to said decimal computing wheel.

2. The combination with a decimal dial wheel, of an ultra-decimal dial wheel lower 70 in denomination than said decimal dial wheel, a gear below said ultra-decimal dial wheel driven thereby, a second gear driven by said first gear, a one-toothed starting member driven by said second gear, a third 75 gear driven by said starting member, a rotatable member driven by said third gear extending to a point above said ultra-decimal dial wheel, and means, including a carry-over wheel fixed on said rotatable member above said ultra-decimal dial wheel, for 80 driving said decimal dial wheel when said ultra-decimal dial wheel completes a revolution.

3. In a combined typewriting and computing machine, the combination with a traveling carriage and a master wheel, of a totalizer comprising decimal dial wheels and computing wheels constantly in mesh with 85 said dial wheels, a non-decimal dial wheel, 90 a computing wheel for said non-decimal dial wheel, a gear between said last-named computing wheel and its dial wheel, and a separately revoluble section of said last-named computing wheel adapted to be revolved separately by its dial wheel to effect carry-overs.

4. In a combined typewriting and computing machine, the combination with a traveling carriage and a master wheel, of a totalizer comprising decimal dial wheels and computing wheels constantly in mesh with 100 said dial wheels, a non-decimal dial wheel, a computing wheel for said non-decimal dial wheel, a gear between said last-named computing wheel and its dial wheel, a separately 105 revoluble portion of said computing wheel to effect carry-overs, and gearing between said separately revoluble portion and its dial wheel adapted to intermittently rotate 110 said portion to effect carry-overs.

5. In a combined typewriting and computing machine, the combination with a master wheel and a traveling carriage, of 115 decimal dial wheels, a common axle for said dial wheels, decimal computing wheels, a common axle for said computing wheels, a non-decimal dial wheel journaled on the decimal dial wheel axle, a special computing wheel for said non-decimal dial wheel journaled on the computing wheel axle, said special computing wheel being offset from its dial wheel, a gear between said special computing wheel and its dial wheel, to cause 120 them to always revolve together, and a separately revoluble portion of said special computing wheel geared to said non-decimal dial wheel to effect carry-overs therefrom.

6. In a combined typewriting and computing machine, the combination with a 130

- 6
- master wheel and a traveling carriage, of decimal dial wheels, a common axle for said dial wheels, decimal computing wheels, a common axle for said computing wheels, a 5 non-decimal dial wheel journaled on the decimal dial wheel axle, a special computing wheel for said non-decimal dial wheel journaled on the computing wheel axle, said special computing wheel being offset from its 10 dial wheel, a differential gear between said special computing wheel and its dial wheel, to cause them to always revolve together, a separately revoluble portion of said special computing wheel, a train of gearing between 15 said non-decimal dial wheel and said separately revoluble portion, and a tooth in said gearing adapted to intermittently rotate said separately revoluble portion to effect carry-overs.
- 20 7. In a combined typewriting and computing machine, the combination with decimal dial wheels, all turning in one direction, and a computing wheel for each dial wheel, constantly in mesh with its dial wheel, of a 25 non-decimal dial wheel, a computing wheel for said non-decimal dial wheel, and connections whereby said non-decimal dial wheel revolves in the opposite direction from said decimal dial wheels.
- 30 8. In a combined typewriting and computing machine, the combination with a traveling carriage and a letter-feeding escapement therefor, of a master wheel, a pair of decimal dial wheels adjacent each other, a computing 35 wheel for each dial wheel and constantly engaging its wheel, printing keys for the typewriter adapted to revolve said master wheel, and to print in successive letter-spaces to effect computations on said dial 40 wheels, a non-decimal dial wheel, a special computing wheel for said non-decimal dial wheel adapted to be engaged by the master wheel at the next adjoining letter-space, and a gearing adapted to cause decimal rotations 45 of the special computing wheel to be carried as non-decimal rotations into the non-decimal dial wheel.
9. In a combined typewriting and computing machine, the combination with a 50 traveling carriage and a letter-feeding escapement therefor, of a master wheel, a pair of decimal dial wheels adjacent each other, a computing wheel for each dial wheel and constantly engaging its dial wheel, printing 55 keys for the typewriter adapted to revolve said master wheel, and to print in successive letter-spaces to effect computations on said dial wheels, a non-decimal dial wheel, a special computing wheel for said non-decimal 60 dial wheel adapted to be engaged by the master wheel at the next adjoining letter-space, a gearing adapted to cause decimal rotations of the special computing wheel to be carried as non-decimal rotations into the 65 non-decimal dial wheel, a separately revoluble portion of said special computing wheel, a sleeve on which said portion is fast, and forming a journal for the other portion of said wheel, and a gear on said sleeve forming part of a carry-over device for said 70 wheel.
10. The combination with a plurality of decimal dial wheels and a plurality of computing wheels therefor, each constantly in mesh with its dial wheel, all said wheels being of uniform size, of a non-decimal dial wheel, a computing wheel therefor of the same size as the other computing wheels, and a differential gear between said last-named computing wheel and said non-decimal dial wheel adapted to cause decimal rotations of the computing wheel to be converted into non-decimal rotations of the dial wheel.
11. In a computing machine, the combination with a traveling carriage and a master wheel, of decimal dial wheels, a non-decimal dial wheel, a computing wheel for each dial wheel and having teeth, and geared thereto so that each computing wheel always turns with its dial wheel, and a single bar adapted to have locking engagement with the teeth of all said computing wheels, and to be released therefrom to enable computations to be effected.
12. In a computing machine, the combination with a traveling carriage and a master wheel, of decimal dial wheels, a non-decimal dial wheel, a computing wheel for each decimal dial wheel, a special computing wheel for the non-decimal wheel, said last-named computing wheel comprising two separately revoluble portions, and a bar universal to all the computing wheels adapted to lock them and to be released therefrom to enable them to be turned to effect computations.
13. In a computing machine, the combination with decimal dial wheels and decimal computing wheels, having teeth, adapted to effect carry-overs for said dial wheels, of a non-decimal dial wheel, a special computing wheel for said non-decimal dial wheel, said last-named computing wheel having teeth identical with the other computing wheels, and also having a portion adapted to be separately driven to effect carry-overs, carry-over wheels relatively to which said computing wheels travel, and a train of gearing on the side of said non-decimal wheel, away from the decimal wheel, connecting said non-decimal wheel to the separately revoluble portion.
14. In a computing machine, the combination with a series of decimal dial wheels, and a series of decimal computing wheels therefor, of a master wheel, a non-decimal dial wheel, a non-decimal computing wheel therefor, said non-decimal computing wheel and non-decimal dial wheel being of the

- same size as the respective decimal dial and computing wheels, carry-over wheels relatively to which said dial and computing wheels travel as a unit, and gearing between 5 the non-decimal computing wheel and the non-decimal dial wheel to enable the master wheel and the carry-over wheels to carry-over non-decimal units therefrom into the decimal dial wheels.
- 10 15. In a computing machine, the combination with decimal wheels and a non-decimal wheel, of a computing wheel for each decimal and non-decimal wheel constantly meshing therewith, a master wheel adapted 15 to engage said computing wheels successively to turn them, and carry-over wheels for connecting said computing wheels to effect carry-overs, said non-decimal computing wheel being in two portions, one portion 20 being differentially geared on one side of said non-decimal wheel to effect turning thereof, and the other portion being differentially geared to the other side to effect carry-overs therefrom.
- 25 16. In a computing machine, the combination with decimal wheels and a non-decimal wheel, of a computing wheel for each decimal and non-decimal wheel constantly meshing therewith, a master wheel adapted 30 to engage said computing wheels successively to turn them, and carry-over wheels for connecting said computing wheels to effect carry-overs, the computing wheel for said non-decimal wheel being in two portions, one portion being differentially geared to one side of said non-decimal wheel to effect turning thereof, and the other portion being differentially geared to the other side to effect carry-overs therefrom; the gearing 35 40 to effect turning being constantly in mesh, and the gearing to effect carry-overs comprising a gear wheel having a toothed and a toothless portion adapted to intermittently be effective.
- 45 17. In a computing machine, the combination with decimal dial wheels and decimal computing wheels constantly in mesh therewith, of a master wheel, identical carry-over wheels for connecting said computing wheels 50 together to effect carry-overs, a non-decimal dial wheel, and a non-decimal computing wheel comprising two separately revoluble portions, one portion being constantly in driving relation with its dial wheel to enable 55 the master wheel to turn it, and the other portion adapted to be separately turned to effect carry-overs.
- 55 18. In a computing machine, the combination with decimal dial wheels and decimal computing wheels constantly in mesh therewith, of a master wheel, identical carry-over wheels for connecting said computing wheels together to effect carry-overs, a non-decimal dial wheel, a non-decimal computing wheel comprising two separately revoluble 60 portions, one portion being constantly in driving relation with its dial wheel to enable the master wheel to turn it, and the other portion adapted to be separately turned to effect carry-overs.
- 65 19. In a combined typewriting and computing machine, the combination with a traveling carriage and a master wheel, of a totalizer comprising decimal dial wheels and computing wheels constantly in mesh with said dial wheels, a non-decimal dial wheel, 70 a computing wheel for said non-decimal dial wheel, a gear between said last-named computing wheel and its dial wheel, a separately-revolvable section of said last-named computing wheel adapted to be revolved 75 separately by its dial wheel to effect carry-overs, typewriter keys adapted to drive said master wheel decimal, and a typewriter key adapted to drive said master wheel so that it will turn more than nine units, 80 said last-named key adapted to simultaneously print the digits representing the number of units the master wheel turns.
- 85 20. In a computing machine, the combination with a master wheel of less than letter-space width, and a series of carry-over wheels of substantially letter-space width, of a traveling totalizer comprising decimal dial wheels, a non-decimal dial wheel, computing wheels constantly in mesh with said 90 decimal dial wheels and adapted to coöperate with said carry-over wheels, a computing wheel for said non-decimal dial wheel having the same number of teeth as said computing wheels for the decimal dial 95 wheels, all of said computing wheels being brought into mesh with said master wheel during their travel past the same, gearing through which said non-decimal dial wheel is driven a number of steps 100 corresponding to the number of steps its computing wheel is actuated, an auxiliary wheel of the same number of teeth as said computing wheels and positioned to be brought into mesh with said carry-over 105 wheels when brought into the computing zone, and a non-decimal-dial-wheel-actuated train of gearing for advancing said auxiliary wheel one step at the completion of a rotation of said non-decimal dial wheel, 110 thereby effecting carry-over through one of said carry-over wheels to the non-decimal dial wheel of lowest order by means of its computing wheel.
- 115 21. The combination with a decimal dial wheel, of a non-decimal dial wheel lower in denomination than said dial wheel, a rotatable member, a computing wheel for said non-decimal dial wheel mounted on said rotatable member for rotation with respect 120 125 130

- thereto, gearing whereby said computing wheel drives said non-decimal dial wheel, and means to effect carry-over from said non-decimal dial wheel to said decimal dial wheel comprising a gear fixedly mounted on said rotatable member between said dial wheels, and means whereby said rotatable member is driven by said non-decimal dial wheel.
- 10 22. In a computing machine, the combination with a master wheel of less than letter-space width, and a series of carry-over wheels of substantially letter-space width, of a traveling totalizer comprising decimal 15 dial wheels, a non-decimal dial wheel, means for actuating said decimal dial wheels including a computing wheel for each of them, a computing wheel for said non-decimal dial wheel spaced from the other computing 20 wheels, all of said computing wheels being brought into mesh with the master wheel during the movement of the totalizer past said master wheel, means for driving said non-decimal dial wheel from its computing wheel the same number of steps that any one 25 of said decimal dial wheels would be driven if its computing wheel were actuated to the same extent, an auxiliary wheel of the same radius as and in alinement with said computing wheels, said auxiliary wheel being 30 narrow and so spaced that it will not be in mesh with said master wheel when the totalizer is at rest, and means, actuated by the computing wheel for the non-decimal dial wheel, to drive the auxiliary wheel one 35 step at the completion of a rotation of said non-decimal dial wheel, and thereby carry over to the decimal dial wheel of lowest denomination through the carry-over wheel in mesh with the auxiliary wheel and the computing wheel for the decimal dial wheel of 40 lowest order.
